UNITED STATES PATENT OFFICE

2,639,825

VEHICLE-MOUNTED HOISTING APPARATUS

Lourie L. Eakin, Ventura, Calif.

Application May 6, 1947, Serial No. 746,248

5 Claims. (Cl. 214—77)

1

My invention relates to hoisting apparatus, and particularly to a transporting vehicle, such as a motor truck, having means incorporated thereon for hoisting relatively heavy objects and placing them on and removing them from the platform of the truck. The present invention is concerned with a hoisting apparatus of the general type disclosed in my pending application for patent on Vehicle Hoist, Serial No. 712,652, filed November 27, 1946, now Patent No. 2,575,262. The prior application is directed to a novel form of hoisting boom for use on motor trucks, while the present application embodies actuating means for pivoting such a boom forwardly and rearwardly of the truck.

One object of my invention is to provide a mobile hoisting apparatus preferably including a motor truck having a platform, a boom pivoted on an axis transversely of the truck platform adjacent the rearward end thereof to adapt it to pivot to an extended position projecting rearwardly from the platform to receive a load which is attached to the end of a cable carried by the boom, and to a retracted position toward the forward end of the vehicle to cause the object to be disposed over the platform so that it may be lowered onto the platform. The invention further provides a novel power-actuated means for pivoting the hoisting boom to its different angular positions.

It is desirable in hoisting apparatus of this general type that the hoisting boom be adapted to pivot through substantially 180 degrees, that is, from a horizontal position extending forwardly from its pivot to a horizontal position projecting rearwardly from the truck, so that the end of the boom may be lowered to a point close to the ground or to the object which is to be raised. It is preferable that hydraulic power means be employed for pivoting the boom in order to obtain the power necessary to pivot the boom when relatively heavy objects are being lifted. In such apparatus, it is the usual practice to operatively connect the piston of a hydraulic actuating jack to a relatively short arm projecting from the pivot of the boom in a downward direction. Since the boom moves through substantially 180 degrees the arm likewise swings through the same angle, and at the extreme forward and rearward movement of the arm the arm and piston approach alignment and this has the effect to cause a substantially "dead center" condition. Due to this condition, a tremendous amount of power is required to obtain the mechanical advantage necessary to

overcome the weight of the boom and its supported load. It is a further object of this invention to provide means for augmenting the power produced by the usual hydraulic jack at the start of the upward pivoted movement of the boom, so that adequate power is provided for overcoming inertia of the boom and initiating its upward tilting movement. This object can best be accomplished by the provision of auxiliary or secondary fluid-actuating jacks, which are operatively connected to the pivotal end of the boom only when the latter is at the forward and rearward extremities of its pivotal movement, these jacks thus functioning to assist the main hydraulic jack in overcoming inertia of the lifting boom. After the boom has been tilted upwardly to a position wherein a greatly improved mechanical advantage exists, sufficient power is derived from the main hydraulic jack to complete the pivotal movement of the boom, and at this point the operation of the auxiliary jacks is arrested. By providing a pair of the auxiliary fluid-actuated jacks and locating one forwardly and one rearwardly of the pivot of the boom, they may be selectively operated to assist in initially tilting the boom upwardly from both forward and rearward positions, and this is an important object of my invention.

It is another object of the invention to provide means for cushioning the load when lowering the boom, and, in this respect, I make use of the auxiliary fluid-actuated pistons which limit the downward tilting movement of the boom and which may be actuated in a manner to positively control the final downward swinging movement, to ease the boom slowly and safely downwardly even when large loads are sustained thereby.

Another object is to provide, in a hoisting apparatus of the character referred to, a hoisting boom of novel construction, capable of sustaining great loads, and one which, when in its forward inoperative position, will not interfere with objects located on the truck platform or other parts of the vehicle. Preferably, the boom is of angular shape so that its distal end is adapted to either overlie the cab of the truck, in close proximity thereto, or to be disposed closely adjacent the rear side of the cab when the boom is in its forward inoperative position, thus avoiding the possibility of the boom projecting above the truck to a height where it might interfere with the driving of the vehicle and where it might strike trees, wires, bridges, and other overhead objects.

Further objects of the invention are set forth in the following specification which describes several preferred embodiments thereof, by way of example, as illustrated by the accompanying drawings. In the drawings:

Fig. 1 is a side elevational view of a motor truck equipped with one form of hoisting apparatus, in accordance with my invention;

Fig. 2 is a plan view of the rearward end of the truck, with the platform thereof removed to disclose the fluid-actuated means for operating the hoisting boom;

Fig. 3 is a longitudinal sectional view, taken substantially on line 3—3 of Fig. 2, and showing the relationship of the parts of the actuating means when the boom is in its forward retracted position;

Fig. 4 is a view similar to Fig. 3, but illustrating the relationship of the parts when the boom is in its rearmost, extended position;

Fig. 5 is a rear view of the truck platform and the hoisting boom, in reduced scale, showing the boom in substantially upright position;

Fig. 6 is a view similar to Fig. 1, but illustrating a different form of hoisting boom, and embodying a modified actuating means therefor;

Fig. 7 is a plan view of the modified actuating means;

Fig. 8 is a longitudinal sectional view, taken on line 8—8 of Fig. 7, showing the relationship of the parts of the actuating mechanism when the boom is in retracted position; and,

Fig. 9 is a view similar to Fig. 8, but showing the relationship of the parts when the boom is in rearmost position.

Referring first to Figs. 1 to 5 of the drawings, my improved hoisting apparatus is therein shown as installed on a conventional motor truck 10, which is provided with a platform 11 for supporting various objects during transportation, and a driver's cab 12 mounted on the chassis 13. Fixed to the side rails 14 of the chassis 13 are tubular bearings 15 which are adapted to receive a tubular axle or pivot member 16 to adapt the latter to rotate on an axis extending transversely of the truck, beneath its platform 11. Welded or otherwise secured to the ends of the tubular axle 16 are the ends of the arms 19 of a hoisting boom 20. The arms 19 extend parallel to the lateral edges of the platform 11. At a suitable distance forwardly of the axle 16 they are inclined upwardly and inwardly (Figs. 1 and 5), and then extend substantially horizontally so that their convergent ends meet. Through this construction the distal end of the boom is disposed above the cab 12 of the truck in relatively close relation thereto, to provide compactness and prevent the end from projecting upwardly to an extent where it might strike overhead wires, trees, and the like. In the present improved boom 20, the convergent arms 19 are joined by a cross-strut 21 which provides rigidity. At the point of joinder of the arms 19, a V-shaped element 22 is secured, this element being adapted to rotatably support a grooved pulley or sheath 23. A cable 24 passes over the sheath 23 and has a hook 25 at one end. The other end of the cable 24 is wound around the drum 26 of a power winch, indicated at 27, such means not being herein shown in detail as they may be of any suitable type generally employed in hoisting equipment.

The hoisting boom is adapted to be pivoted to any of the positions indicated in Fig. 1 by means of fluid-actuated devices, to be next described.

The pivot tube or axle 16 has a pair of radial arms 30, which may be welded thereto, each arm 30 being preferably made in two complementary parts thereby providing a space therebetween for receiving the end of a piston rod 31 of a main hydraulic jack 32, the rods 31 being pivotally connected to the arms 30 by pins 33. Each rod 31 carries a piston 34 at its forward end, the pistons being slidable in hydraulic cylinders 35 which are pivotally connected to brackets 36 carried by a cross-member 37 of the vehicle chassis 13. The ends of the cylinders 35 are connected by hydraulic lines 38 and 39 which lead to a manually-operable valve 40 (Fig. 2), which may be actuated to selectively introduce fluid under pressure into either end of the cylinders to actuate their pistons 34 which act through their rods 31 and the arms 30 to turn the pivot tube or axle 16 in either direction to swing the boom 20 between its two extents of movement illustrated by full lines and dot-and-dash lines in Fig. 1. While the main hydraulic jacks 32 function to move the boom 20 through the major portion of its pivotal movement, the movement of the boom at the extreme forward and rearward ends of its movement is controlled by auxiliary fluid-actuated means, to be presently described.

It will be observed by reference to Figs. 3 and 4 that when the boom is at the extent of its forward and rearward movement, the arms 30 extend nearly horizontal and an almost "dead center" relation exists between the arms 30 and the piston rods 31. Because of this very unfavorable leverage condition, and due to the fact that the great inertia caused by the heavy boom and the weight supported thereby must be overcome, torque of great magnitude must be applied to the axle 16, and, since the moment arm 30 is relatively short, it is apparent that tremendous power is required to produce such force. For this reason it is very desirable, and quite essential, that the main hydraulic-actuating means be assisted during the start of the pivotal movement of the boom upwardly from its extended and retracted horizontal positions. In the present invention this assisting means consists of auxiliary or secondary fluid-actuated means to be next described.

Secured to cross-members 39 of the chassis 13, forwardly of the axle 16, is a hydraulic cylinder 44 in which a piston 45 is slidable. The piston 45 has a rod 46 which extends rearwardly and has a cross-piece or follower 47 at its end. The upper portion of the follower 47 is adapted to slide along a pair of guiding strips 48 extending longitudinally of, and attached to, the chassis 13. Secured to a cross-member 49 of the chassis, rearwardly of the pivot-tube or axle 16, is a second hydraulic cylinder 50 in which a piston 51 is slidable toward and away from the axle. The rod 52 of the piston 51 has a follower 53, the upper portion of which is adapted to slide forwardly and rearwardly along a pair of guiding strips 54. The auxiliary pistons 45 and 51 are slid in their respective cylinders by fluid introduced under pressure into the opposite ends of the cylinders through lines 55, 56, 57, and 58, the flow through the lines being controlled by a valve 60.

The followers 47 and 53, of the respective hydraulic piston rods 46 and 52, are adapted to engage the opposite edges 65 and 66 of a wedge-shaped cam member 67 secured to and projecting radially from the pivot-tube 16. Assuming that the boom 20 is in its forward retracted position,

as shown by full lines in Figs. 1 and 3, the followers 47 and 53 will assume the positions shown in the latter view. That is to say, the follower 47 is disposed close to the axis of the pivot-tube 16, and the follower 53 is located at a greater distance from the tube with the outer edge 66 of the cam member 67 resting thereagainst. The boom 20 is thus maintained at rest in its forward inoperative position with its cam member 67 resting against the follower 53, which serves as a stop for limiting the tilting movement of the boom in this direction.

To pivot the boom 20 to the extended position, indicated by dot-and-dash lines in Figs. 1 and 4, to adapt it to lift a heavy object, such as that shown at 70, hydraulic fluid is introduced into the right-hand ends of the main hydraulic-actuating cylinders 35 and the auxiliary-actuating cylinder 50. The main piston rods 31, being connected to the arms 30, tend to rotate the pivot-tube 16 in clockwise direction to thereby pivot the boom 20 in the same direction. During this initial pivotal movement, the follower 53 of the piston rod 52 is forced forwardly, and, acting between the strips 54 and the inclined edge 66 of the cam member 67, forces the latter downwardly, in the manner indicated by dot-and-dash lines in Fig. 4. In this manner, the auxiliary hydraulic means 50 augments the force applied by the main hydraulic means 32 through the arms 30 to the axle 16, so that the torque necessary to overcome inertia of the boom is readily attained. The movement of the follower 53 is relatively short, but is sufficient to swing the cam member 67 downwardly through an angle of approximately 30 degrees, it having been determined that when the arms 30 are moved to this position the main hydraulic means 32 is able to complete the pivoting of the boom 20 without assistance. It is thus seen that the initial pivotal movement of the boom is effected by the combined action of the main and auxiliary hydraulic means 32 and 50, while the remainder of the pivotal movement is produced by the main means alone.

As the boom 20 approaches the extent of its rearward extended movement, the edge 65 of the cam member 67 strikes the follower 47 of the piston rod 46 of the auxiliary hydraulic means 44 in the manner shown by full lines in Fig. 4. Thereafter the valve 60 is actuated to cause fluid to be introduced into the right-hand end of the cylinder 44, to retract the follower 47 along the guiding strips 48. In this manner, the follower 47 slides forwardly along the inclined cam edge 65 to permit further pivotal movement of the boom in clockwise direction. Thus, the boom 20 is permitted to complete its pivotal movement to the fully extended position indicated by dot-and-dash lines in Figs. 1 and 4. During this movement, the main cylinders 35 pivot on the brackets 38. The valves 40 and 60 may be made as a unit or coupled together in any suitable manner, so that proper synchronization of the actuation of the main and auxiliary hydraulic means can be effected.

After the boom 20 has been extended, the end of the cable 24 may be connected to the object 70, after which the sequence of operations is reversed to cause the boom to swing upwardly in counterclockwise direction to lift the object and move it to any position above the truck platform. The power winch 27 is first operated to cause the cable 24 to lift the object 70 off the ground, and the valves 40 and 60 are then actuated to effect op-

eration of the hydraulic means. The initial pivotal movement of the boom 20 is effected by the simultaneous actuation of the main and secondary hydraulic means 35 and 44. As the piston rod 46 is slid rearwardly, its follower 47 is forced between the guiding strips 48 and the cam edge 65 so as to cause the cam member 67 to be forced downwardly, as shown by full lines in Fig. 4. The combined forces thus applied to the pivot tube 16 by the pistons 34 and 45 through the arms 30 and the cam member 67 produces the torque necessary to overcome the combined weight of the lifting boom 20 and the object 70 supported thereby, and thus the boom is tilted upwardly in counterclockwise direction. After the cam member 67 arrives at the position shown by full lines in Fig. 4, the auxiliary hydraulic means 44 has no further function and comes to rest, the remainder of the pivotal movement of the boom being effected by the main hydraulic means 32, which may be actuated for a period necessary to carry the object 70 above the location on the truck platform where it is desired to support it during transportation. The boom 20, being of a bifurcated construction, permits the object 70 to be swung between its side members, as shown by dash lines in Fig. 1, and it will be noted that the cable 24 passes across the connecting strut 21 of the boom to prevent excessive swinging movement of the object so that it can be deposited on the platform 11 with greater accuracy. When the object 70 is disposed in the proper location, the valve 40 is manipulated to arrest the operation of the main hydraulic jacks 32, after which the cable 24 is payed out from the drum 26 to lower the object onto the platform. While the object 70 herein shown is one which may be set upon the platform, it will be apparent that the boom 20 is capable of lifting and supporting other objects, such as poles, in upright position, to permit them to be erected in holes in the ground. The hoisting apparatus may thus be said to be universal in its application to use, and may be advantageously employed on transportation and construction vehicles. Moreover, the hoisting equipment may be readily applied to existing trucks with minimum change in their structures.

The modified construction of the hoisting apparatus shown in Figs. 6 to 9 is similar to that shown in the preceding views, and the apparatus operates to accomplish the same results. In this alternative structure, a slightly different type of lifting boom 80 is shown as pivotally mounted on the truck 81. The boom 80 has opposite legs 82 which, when the boom is in fully retracted position, extend along the side of the platform 83 of the truck, the rearward ends of the legs being connected to the ends of a transversely extending pivot-tube or axle 84. At a point adjacent the rear of the cab 85 of the truck, the legs 82 project upwardly, as shown at 86, and above the top of the cab, they extend inwardly to provide horizontal connecting portions 87 (Fig. 7). Between the adjoining ends of the portions 87, a cable sheave 88 is rotatably connected, a cable 89 passing therearound having a hook 90 at its end. The cable 89 is connected to a power winch 91, as in the first embodiment of the invention. The angularly-shaped boom 20 is adapted to pivot from the retracted position, shown by full lines, to the extended position, indicated by dot-and-dash lines in Fig. 6, and vice versa. A cross-strut 92 preferably connects the upright portions 86 of the boom, and, when the boom is in its extended position, the cable 89 passes across this strut, and

thus interference of the cable with the truck platform or objects thereon is avoided.

As in the first construction, the boom 80 is pivoted throughout the major portion of its movement by main hydraulic means 100, while its initial movement is effected by the combined actuation of the means 100 and auxiliary hydraulic means 101 and 102. The main hydraulic means includes a pair of pivoted cylinders 103 in which pistons 104 are adapted to slide, the pistons having rods 105 pivotally connected to arms 106 projecting radially from the pivot-tube or axle 84. The auxiliary hydraulic means 101 and 102 consist of cylinders 109 and 110, respectively, which are affixed to cross-members 111 of the truck chassis. Pistons 113 and 114 slidably in the cylinders 109 and 110 have rods 115 and 116, the lower ends of which are adapted to engage ears 117 and 118 projecting laterally in opposite directions (Fig. 7) from an arm 119 fast on the axle 84.

When the boom 80 is in forward retracted position, the piston rod 116 is retracted in the cylinder 110, and the arm 119 is disposed in the substantially horizontal, rearwardly extending position, shown in Figs. 7 and 8, with the ear 118 engaged with the lower end of the piston rod. To pivot the boom 80 toward a rearward extended position hydraulic fluid is introduced simultaneously into the right-hand end of the main cylinder 103 and the upper part of the auxiliary cylinder 110. The piston rods 105, acting through the arms 106, tend to rotate the axle 84 in clockwise direction, and this operation is augmented by the piston rod 117 which, through its engagement with the ear 116 of the arm 119, forces the latter downwardly, as indicated by dot-and-dash lines in Fig. 9. When the piston rod 116 completes its movement in this direction, the piston rod 105 operates alone to complete the pivotal movement of the boom. As the boom 80 and arm 119 arrive at the position indicated by dash lines in Fig. 8, the ear 117 of the arm 119 engages the end of the auxiliary piston rod 115 to cushion the descent of the boom. The piston rod 115 is then retracted into the cylinder 109, as shown in Fig. 9, to permit further pivotal movement of the boom to fully extended position.

After the cable 89 is connected to an object 120, as shown in Fig. 6, hydraulic fluid is introduced into the left-hand ends of the main cylinders 103 and into the upper end of the auxiliary cylinder 109. The piston rod 115 thus forces the arm 119 downwardly, to the position shown by dash lines in Fig. 8, after which the main piston rods 105 complete the tilting movement of the boom toward its forward retracted position. When the object 120 is positioned over the area of the platform 83, where it is to be deposited, the actuation of the main hydraulic means 100 is arrested and the object lowered by paying out the cable 89 from the drum 91. The introduction of hydraulic fluid into the opposite ends of the cylinders 103, 109, and 110, may be controlled by a suitable valve or valves, not herein shown.

While I have herein shown and described the improved hoisting apparatus, as embodied in two preferred forms of construction and applied to use with a particular type of vehicle, by way of example, it will be apparent that the construction of the apparatus and its application to use may be varied in certain respects without departing from the spirit or scope of the invention.

Therefore, without limiting myself in this respect, I claim:

1. In a vehicle, hoisting means for loading objects on and unloading them from the vehicle, including: a boom pivoted transversely of the vehicle to adapt it to pivot to a forward position overlying the vehicle, to a rearward position projecting rearwardly from the vehicle, and to positions intermediate said forward and rearward positions, said boom having an arm and a stop element projecting radially from its pivotal end; primary fluid actuated means connected to said arm and operable to pivot said boom through the major portion of its movement in either direction; a pair of secondary fluid actuated pistons disposed forwardly and rearwardly respectively of the pivotal point of the boom and adapted to be moved to extended position to engage said stop element to limit the pivotal movement of said boom, and adapted to be moved to retracted position to permit said boom to complete its pivotal movement to extreme forward and rearward positions under the influence of gravity, said pistons being also operative, upon movement to extended position, to initially pivot said boom in a direction away from its forward and rearward positions.
2. In a vehicle, hoisting means for loading objects on and unloading them from the vehicle, including: a boom pivoted transversely of the vehicle to adapt it to pivot to a forward position overlying the vehicle, to a rearward position projecting rearwardly from the vehicle, and to positions intermediate said forward and rearward positions, said boom having an arm and a stop element projecting radially from its pivotal end; primary fluid actuated piston means connected to said arm and operable to pivot said boom through the major portion of its movement in either direction; a pair of secondary fluid actuated pistons disposed forwardly and rearwardly respectively of the pivotal point of the boom and adapted to be moved to extended position to engage said stop element to limit the pivotal movement of said boom, and adapted to be moved to retracted position to permit said boom to complete its pivotal movement to extreme forward and rearward positions under the influence of gravity, said pistons being also operative, upon movement to extended position, to tilt said stop element to initially pivot said boom in a direction away from its forward and rearward positions.
3. In a vehicle, hoisting means for loading objects on and unloading them from the vehicle, including: a boom pivoted transversely of the vehicle to adapt it to pivot to a forward position overlying the vehicle, to a rearward position projecting rearwardly from the vehicle, and to positions intermediate said forward and rearward positions, said boom having an arm and a cam projecting from its pivotal end; primary fluid actuated piston means connected to said arm and operable to pivot said boom through the major portion of its movement in either direction; a pair of secondary fluid actuated pistons disposed forwardly and rearwardly respectively of the pivotal point of the boom, and adapted to be moved to extended position to engage said cam to limit the pivotal movement of said boom, and adapted to be moved to retracted position to permit said boom to complete its pivotal movement to extreme forward and rearward positions under the influence of gravity, said secondary pistons being also operative, upon movement to extended position and relative to said cam, to initially pivot

said boom in a direction away from its forward and rearward positions.

4. A vehicle hoist comprising a frame, a boom pivoted on said frame for movement from a position extending in one direction from the axis of the pivot to an intermediate raised position and to a position extending in the other direction, an arm extending from the pivotal end of the boom, a primary fluid actuated cylinder and piston operatively connected to said frame and said arm for moving said boom from one position to another, a cam arm extending from said pivotal end of said boom, a first auxiliary fluid cylinder and piston operative between said frame and said cam arm for initially moving said boom from its said position extending in one direction for assisting said primary cylinder and piston, and a second auxiliary fluid cylinder and piston operative between said frame and said cam arm for assisting said primary cylinder and piston for initially moving said boom from its position extending in the said other direction.

5. A vehicle hoist comprising a frame, a boom pivoted to said frame for movement from an extreme position extending in one direction from the axis of the pivot to an intermediate position and to an extreme position extending in the other direction from said pivot, an arm extending from the pivotal end of the boom, a primary fluid actuated cylinder and piston operatively connected to said frame and said arm for moving said boom from one position to another, a cam arm extend-

ing from said pivotal end of said boom, auxiliary cylinder and piston means mounted on said frame, cam follower means connected to said auxiliary cylinder and piston means and engageable with said cam arm and with said frame, said cam arm having a cam surface contour whereby the principal mechanical advantage is obtained when said boom is at either of its extreme positions whereby said auxiliary cylinder and piston means assists said primary cylinder and piston for initially causing the movement of said boom from said extreme positions.
